UNITED STATES PATENT OFFICE.

ANTON KRIEGHOFF, OF BOSTON, MASSACHUSETTS, ASSIGNOR TO ANTON KRIEGHOFF COMPANY, OF BOSTON, MASSACHUSETTS, A CORPORATION OF MASSACHUSETTS.

PIANO.

1,261,406.

Specification of Letters Patent.

Patented Apr. 2, 1918.

Application filed May 13, 1915. Serial No. 27,927.

To all whom it may concern:

Be it known that I, ANTON KRIEGHOFF, a citizen of the United States, and resident of Boston, county of Suffolk, State of Massachusetts, have invented an Improvement in Pianos, of which the following description, in connection with the accompanying drawing, is a specification, like characters on the drawing representing like parts.

10 The general purpose of this novel construction is to produce a piano in which the vibrating parts (particularly the sounding-board) will be free to perform their functions without detracting from the structural 15 stability and efficiency of the frame necessary to withstand the tension imposed by the strings.

In this novel construction there is employed a sounding-board from which have 20 been eliminated all of the usual wooden bridges. The string plate, which is otherwise of the present general type, has a section thinner than most portions of the plate. This section is therefore relatively flexible 25 and adapted the more freely to take up, and communicate vibratory energy imparted thereto by the strings which are provided with bridges on this section. Sound posts or transmitters connect this section to the 30 sounding-board and serve to communicate the vibrations of the section to the sounding-board.

This section, as shown in the embodiment disclosed herein, is preferably an integral 35 part of the metal string plate. Hitch pins for the treble strings are placed upon the section and a narrow bearing or bridge is formed thereon for the treble strings. The hitch pins for the bass strings are placed 40 upon the string plate while a bridge therefor is provided upon this flexible section. Hence it is obvious that in this embodiment both treble and bass strings are in contact with this flexible section.

45 It is readily apparent that the inventive idea here disclosed may be embodied in widely variant piano structures as also in other musical instruments whether the string actuating means be mechanical, electrical or manual.

An object of this invention is to improve the tonal qualities of musical instruments

by increasing the resonance of the sounding-board through the elimination of bridges thereon.

55 Other objects of the invention will more fully appear from the following description and the accompanying drawings and will be pointed out in the annexed claims.

Figure 1 is a plan view of a piano string 65 plate and sounding board embodying the invention;

Fig. 2 is a section on the line 2—2, Fig. 1;

Fig. 3 is a section on the line 3—3, Fig. 1;

Fig. 4 is a sectional detail of one of the 70 transmitters;

Fig. 5 is a sectional detail of a modified form of transmitter.

The selected embodiment of the invention illustrated is of a structure employed in an 60 instrument of the upright type, but it is obvious that with slight changes, it may be employed in pianos of the grand or other type, or in similar musical instruments.

The cast metal string plate 1 has secured 75 thereto, as in the usual construction, the sounding-board 2 of the well-known type. The string plate is reinforced by transverse braces 4 to insure rigidity under the enormous strain induced by the piano strings 80 when in position under the usual tension. In place of the ordinary treble hitch section, this string plate is provided with a thinner and relatively more flexible section 3. As shown, it is preferably made in the form of 85 an elongated platelike section free at its longer edges and integrally cast at its ends. This section 3 may, of course, be made of any suitably vibratory substance. The section 3, save at its integrally cast ends, does 90 not bear upon or come into contact with other parts of the string plate. The elongated section 3 is flat and, as clearly disclosed in Fig. 1, is preferably curved along the line of its longest dimension. This longitudinal curve affords opportunity to position bridging means for the strings on the section to accommodate the varying lengths of the strings as shown.

The vertical braces 4 have offset portions 5 100 which pass behind and do not touch the section 3 or impede in any manner its free vibration.

The vibrations which are set up in the

flexible section are communicated to the sounding-board 2 by means of a plurality of transmitters.

These transmitters consist each of a metallic post 6 passed through the section 3 and received in threaded engagement with the wooden sounding-board. A block of wood 7 is affixed to the rear face of the sounding-board opposite each post to receive the screw-threaded end of the post. The other end of the post, extending through the section 3, has threaded thereon two nuts 8 turned tightly against the front and rear faces respectively of the section.

15 A modification of the transmitter is shown in Fig. 5. In this form there are a plurality of lugs 9 integrally cast on the rear face of the section which extend a distance so that their ends impinge upon the front face of the sounding-board. These lugs have each a central threaded aperture 10 in which is received a set screw 11. The set screw passes through the sounding-board and is received in threaded engagement with the lug aperture. The washers 12 are carried by the set screw and are firmly pressed against the front and rear faces of the sounding-board.

14 The hitch pins 13 for the treble strings 30 are secured adjacent the upper edge of the section 3. A rib 15 preferably cast integral with this section, extends substantially its length. This rib is positioned adjacent the upper edge of the section and provides 35 a bearing or bridge for the strings leading from the hitch pins 13 over the sounding-board 2, to the usual upper bearing 16 under the pressure bar 17, to the wrest pins 18. These wrest pins 18 in accordance with the 40 usual construction are passed through the metal string plate 1 and are embedded in the wrest plank 19.

21 The hitch pins 20 for the bass strings 45 are mounted on the string plate. A bearing or bridge for the bass strings is preferably 45 also provided on the flexible section. As shown in Fig. 3, this bridge consists of a flange 22 which extends a short distance along the lower edge of the section. Bearing pins 23 are secured thereto and provide 50 a bearing on the flexible section for the bass strings leading from their hitch pins over the section 3 and sounding-board to their respective wrest pins 18.

55 The portions of the treble strings which freely vibrate when struck by the usual hammers are those which are comprehended between the bearing points of the strings on the rib 15 of the flexible section 3 and 60 the usual upper bearing 16 on the piano string plate. The similar freely vibratile portions of the bass strings are those which are comprehended between the bearing-pin flange 22 and the pins on the usual upper 65 bass string bearing. The vibrations of the

various strings are thus directly communicated to the flexible section by means of the treble and bass bearings or bridges. The section, which as conditions demand is made more or less flexible and resilient and 70 free to vibrate throughout its area, readily receives and takes up the string vibrations.

Vibratory energy imparted to the section is communicated to the sounding-board by means of the transmitters so located with 75 reference to the section as efficiently to convey the sound vibrations. The sounding-board, energized through the medium of these transmitters and being without longitudinal bridges or braces thereon, vibrates 80 freely substantially throughout its area.

This invention removes the usual bridges from the sounding-board and places them on the string plate and leaves the sounding-board entirely free therefrom. And, in the 85 employment of this flexible section, vibrantly energized through the intermediary of the string bearings thereon, and, directly connected to a bridgeless sounding-board, more perfect, intensified and full tones are 90 derived. Further, the production cost is lowered, the construction is simpler, is composed of fewer parts and the structural efficiency of the assembled whole is augmented. It is to be understood that the construction 95 disclosed herein is illustrative but not restrictive and that the same may be modified within the meaning and scope of the claims which follow.

What I claim is:

1. In a musical instrument, a string plate, a sounding board, strings, the string plate having an elongated platelike section more flexible than the remainder of the string-plate, means by which the vibrations of the 105 strings may be communicated to said section, and means for communicating the vibrations of said section to the sounding-board.

2. In a musical instrument, a string plate, a sounding-board, the string plate having 110 an elongated platelike section more flexible than the remainder of the string-plate, strings, bridges for the strings on said section by which the vibrations of the strings may be communicated to said section, and 115 means for communicating the vibrations of said section to the sounding-board.

3. In a musical instrument, a string-plate, a sounding-board, strings, the string plate having an elongated section free at its longer 120 edges and integrally attached at its ends, bridges on said section for the strings whereby the vibrations of the strings may be communicated to said section, and means for communicating the vibrations of the section 125 to the sounding-board.

4. In a musical instrument, a string plate, a sounding-board, strings, the string plate having a relatively flexible elongated section integrally attached at its ends, said section 130

having integral bridges for the strings whereby the vibrations of the strings may be communicated to said section, and means for communicating the vibrations of the 5 section to the sounding-board.

5. In a musical instrument, a string plate, a sounding-board, strings, the string plate having a platelike section more flexible than the remainder of the string plate, hitch pins for treble strings on said section, hitch pins on the string plate for the bass strings, bridges on said section for all said strings whereby the vibrations of the strings may be communicated to said section, and means 10 for communicating the vibrations of the section to the sounding-board.
6. In a musical instrument, a string plate, a sounding-board, strings, the string plate having an elongated section more flexible than the remainder of the string-plate, marginal ribs longitudinally disposed on said 15
- 20

section, said section being longitudinally curved and said ribs providing bridges for the strings to communicate the string vibrations to said section, and means for communicating the vibrations of the section to the sounding-board. 25

7. In a musical instrument, a string plate, a sounding-board, strings, the string plate having an elongated section more flexible 30 than the remainder of the string-plate, means adjacent the longer edges of said section providing bridges for said strings to communicate the string vibrations to said section, said section being longitudinally 35 curved, and a plurality of instrumentalities fixedly connected to said section and said sounding-board to communicate the vibrations of the section to the sounding-board.

In testimony whereof, I have signed my 40 name to this specification.

ANTON KRIEGHOFF.
